UNITED STATES PATENT OFFICE.

DOUGLAS L. PARKHURST, OF WASHINGTON, DISTRICT OF COLUMBIA.

TIME SWITCH.

Application filed November 1, 1924. Serial No. 747,359.

(GRANTED UNDER THE ACT OF MARCH 3, 1883; 22 STAT. L. 625.)

To all whom it may concern:

Be it known that I, DOUGLAS L. PARKHURST, a citizen of the United States, residing at Washington, District of Columbia, have invented certain new and useful Improvements in Time Switches, of which the following is a specification.

The invention described herein may be used by the Government or any of its officers or employees in prosecution of work for the Government, or any other person in the United States without payment to me of any royalty thereon, in accordance with the act of March 3, 1883.

15 This invention relates to a time switch for signaling lamps or the like.

The object of the invention is to provide a switch whereby an electrical circuit may be automatically established and broken 20 within a certain period of time.

It is also an important object of the invention that the switch can be adjusted to establish the electrical circuit for any length of time desired within the certain period of 25 time.

A still further object of the invention is that the device be exceedingly compact and simple in structure.

Other objects relating to details of construction, combination and arrangement of parts, will hereinafter appear in the detailed description to follow.

The invention is illustrated by way of example in the accompanying drawings in 35 which:

Figure 1 is a schematic view of the switch and an electrical circuit which may be associated therewith;

Figure 2 is a face view of the switch assembly;

Figure 3 is a sectional view taken through the switch assembly substantially on the line 3-3 of Figure 2;

Figure 4 is an exploded view, showing 45 the switch assembly and the associated time shaft;

Figure 5 is a front elevation of the time-setting unit employed in the switch assembly;

Figure 6 is an end view of the same; and

Figure 7 is a detailed plan view illustrating particularly the stationary electrical contact-making fingers employed with the switch assembly.

55 Like reference characters refer to similar

parts throughout the different views of the drawings.

It should be here stated that the switch assembly may be operated by the time shaft of a clock of any suitable type. In Figures 60 3 and 4 the time shaft of a clock is indicated generally by reference numeral 10, and it will be noted the shaft 10 is made to extend a considerable distance from the body of the clock in order that the same may 65 properly accommodate the switch assembly to be hereinafter described.

Upon the shaft 10 there is fitted a bushing 11, which is made of electrical insulating material and terminates at its inner end 70 in a flange or collar 12. A second bushing 13 is fitted upon the first-named bushing 11 and the bushing 13 likewise terminates at its inner end in a flange 14, said flange abutting the flange 12 of the bushing 11. A 75 dial plate 15 is provided and formed with a central opening adapted to receive the bushing 13. The dial plate 15 is fitted upon the bushing 13, as shown to advantage in Figures 3 and 4.

80 The dial 15 has numbers printed or stamped upon its front face to indicate the twenty-four hours constituting a day and a night. Preferably a plurality of short radial lines 16 are provided to indicate hour periods and shorter radial lines 17 are provided to indicate half hour periods.

Upon the bushing 13 there is loosely 85 fitted a sleeve 18 which has secured at its one end a disc 19, and at its other end a disc 20. Between the discs 19 and 20 there is loosely 90 fitted upon the sleeve 18 a ring 21. The ring 21 is formed with the radial extension 22, said extension being disposed in close relation to the front face of the dial 15. The disc 19 is formed with a similar extension 23 and each extension is provided with an offset surface 24 adjacent its one longitudinal edge to provide an edge, which is equal 100 to or exceeds in length a line 16 upon the dial 15. The specific purpose of this arrangement will hereinafter appear.

The ring 21 has formed upon its outer periphery a raised surface 26, and a similar raised surface 27 is formed upon the outer periphery of the disc 20. These surfaces 105 will hereinafter be referred to as cams, and it will be noted that the one end of the cam 26 terminates in a line coinciding with the edge provided by the offset surface 24 of 110

extension 22 while the cam 27 terminates at one end in a similar manner with the edge provided by the offset surface 24 of the extension 23.

- 5 A plate 28 is provided, said plate being of insulating material and having a central opening adapted to receive the outer end of bushing 11. The diameter of this plate slightly exceeds the diameter of the disc 20.
 10 However, it is to be noted that the cams 26 and 27 protrude from the outer periphery of the plate 28, as shown in Figure 2.

The outer end of the time shaft 10 is provided with a threaded longitudinally and 15 centrally extending bore, which is adapted to receive a screw 29, said screw terminating at its outer end in a shoulder 30, which, in turn, is formed with an elongated stem-like extension 31 having its outer end enlarged 20 and knurled, as at 32.

The ring 21 is provided with a suitable threaded opening adapted to receive a screw 33, said screw also terminating at its outer end in a shoulder or enlargement 34, and 25 said enlargement in turn being provided with an extension 35 which terminates in a knurled head 36. Plate 28 is provided with an opening to receive freely shoulder 34 of screw 33. Disc 20 is provided with an arcuate slot to permit independent movement of 30 the member 20 with relation to the ring 21. The slot is best shown in Figure 5. The screw 29 is designed to secure the switch assembly upon the time shaft 10 while the 35 screw 33 is employed for holding the members 19 and 20 against movement with relation to the ring 21. It is also pointed out that the dial plate 15 is tightly fitted upon the bushing 13.

40 Referring to Figures 1 and 7, at 35', there is indicated a block of insulating material which may be supported in any convenient manner, and which carries the contact fingers 36' and 37. The contact finger 37 is 45 bent adjacent its free end to provide a protrusion 42 which is adapted to ride upon the outer peripheral surface of the plate 28. The finger 37 is of such a width that upon the cams 26 and 27 coming into registration 50 therewith, the same will engage the protrusion 42 and lift said finger from the peripheral surface of the plate 28. The finger 36' is adapted to press against the rear face of the dial 15.

55 The block 35' may carry the two binding posts 38, 39, one of which is electrically connected to the contact finger 36' and the other connected to finger 37. The binding post 38 may be connected by a suitable lead to 60 one side of an electric battery generally indicated by the reference numeral 43. The other side of the battery may be connected to the circuit terminal 40 and the binding post 39 connected to a similar circuit terminal 41. The circuit to be controlled by

the switch may be connected to the terminals 40 and 41.

In Figure 1 there is shown a pointer 44, the purpose of which will be explained in the general description of the operation of 70 this invention.

In manufacturing the device, the battery 43, together with the clock for driving the time shaft 10 and the switch assembly, may be placed in one casing and made portable. 75 The signal element to be controlled, such as an electric lamp, should be connected to the terminals 40 and 41. The parts of the switch assembly are brought together as best illustrated in Figure 3.

80 When it is desired to utilize the present invention for operating the signal element connected to the terminals 40 and 41 during a certain interval occurring within the period of twenty-four hours, the switch assembly is set for this purpose. In setting the switch assembly the screw 33 should be removed and the ring 21 and disc 19 rotated to bring their extensions 22 and 23 respectively so that the distance between the 85 edges provided by the offset surfaces 24 will indicate upon the dial 15 the length of time the signal is desired to be operated within a period of twenty-four hours. The screw 33 may now be placed in position and 90 in this way the members 19, 20 and 21 are securely clamped together. The dial 15 should now be rotated to bring the pointer 44 into registration with the time at which the switch is being set. The assembly 95 shown in Figure 5 should now be rotated with respect to the dial 15 to bring the edge 24 of the forward extension to indicate the hour at which the signal is to be operated. The screw 29 should then be operated to 100 secure the plate 28 against the disc 20 and also secure the entire switch assembly upon the time shaft 10.

105 The device when assembled and arranged, as above described, is ready for operation. 110 The time shaft 10 may be set into operation by starting the associated clock and with the turning of the switch assembly, the finger 36 will ride upon the outer periphery of the plate 28 until it is engaged by one 115 of the cams 26, 27. It should be here noted that the time shaft in this particular instance revolves in a counter-clockwise direction. The cam surface 26 would be the first to engage with the finger 37 and extension 120 22 would be the foremost. Immediately upon the finger 37 engaging the cam 26, an electrical current will flow from one side of the battery 43 through the contact fingers 37 and 36' and then through the signal circuit connected to the terminals 40 and 41. 125 The circuit will be maintained until both the cams 26 and 27 pass from beneath the outer end of the finger 37. As is entirely apparent the circuit through the signal ele- 130

ment will be made a certain period during each twenty-four hours, or, in other words, during each complete rotation of the dial 15.

While I have shown and described the 5 preferred form of my invention, I wish it to be understood that I am aware of the fact that slight changes might be made in the general construction, combination and arrangement of parts by those skilled in the 10 art without departing from the spirit of my invention, as indicated by the appended claims.

I claim:

1. In an electric time switch, a time shaft, 15 a pair of metallic annular plate members mounted upon the shaft in abutting relation, a disc of insulating material mounted upon the shaft, said disc of insulating material exceeding the diameter of the metallic plate members, an elongated peripheral contact carried by each metallic plate member, said contacts extending beyond the periphery of the disc of insulating material, a stationary contact arm adapted to ride 20 upon the periphery of the disc of insulating material and also overlap the peripheries of the metallic plate members, and means whereby the metallic plate members may be adjusted to bring the peripheral contacts 25 thereof into overlapping relation and provide various lengths of continuous contacting surface with which said contact arm may engage during each rotation of said time shaft.

3. In an electric time switch, a time shaft, 30 a pair of metallic annular plate members mounted upon the shaft in abutting relation, a disc of insulating material mounted upon the shaft, said disc of insulating material exceeding the diameter of the metallic 35 plate members, an elongated peripheral contact carried by each metallic plate member, said contacts extending beyond the periphery of the disc of insulating material, a stationary contact arm adapted to ride 40 upon the periphery of the disc of insulating material and also overlap the peripheries of the metallic plate members, means whereby the metallic plate members may be adjusted to bring the peripheral contacts 45 thereof into overlapping relation and provide various lengths of continuous contacting surface with which said contact arm may engage during each rotation of said time shaft,

5. In an electric time switch, a time shaft, 50 a pair of metallic annular plate members mounted upon the shaft in abutting relation, a disc of insulating material mounted upon the shaft, said disc of insulating material exceeding the diameter of the metallic 55 plate members, an elongated peripheral contact carried by each metallic plate member, said contacts extending beyond the periphery of the disc of insulating material, a stationary contact arm adapted to ride 60 upon the periphery of the disc of insulating material and also overlap the peripheries of the metallic plate members, means whereby the metallic plate members may be adjusted to bring the peripheral contacts 65 thereof into overlapping relation and provide various lengths of continuous contacting surface with which said contact arm may engage during each rotation of said time shaft, and means for clamping together the metallic plate members and disc of insulating material to move with the shaft as a unit.

3. In an electrical time switch, a time shaft, a sleeve upon the shaft, a pair of disc 60 members fixed upon the sleeve, a ring loosely mounted upon said sleeve and between said disc members, an elongated peripheral contact carried by one of said disc members and the ring, a stationary contact arm 65 ranged to wipe the peripheral contacts, and

means for adjustably securing the ring with relation to said disc members.

4. In an electrical time switch, a time shaft, a sleeve upon the shaft, a pair of disc members fixed upon the sleeve, a ring 70 loosely mounted upon said sleeve and between said disc members, an elongated peripheral contact carried by one of said disc members and the ring, a stationary contact arm arranged to wipe said peripheral contacts, and means whereby the ring may be adjustably clamped to one side of one of said disc members.

5. In an electric time switch, a time shaft, a sleeve upon the shaft, a pair of discs fixed 80 upon the sleeve, a ring between said discs, an elongated peripheral contact carried by one disc and the ring, means whereby the ring and discs may be adjusted with respect to each other, a contact arm arranged to 85 wipe said peripheral contacts with each rotation of said shaft, a disc of insulating material arranged upon said shaft and the periphery of which is adapted to engage the contact arm and hold the same out of 90 contacting relation with said discs and said ring.

6. In an electric time switch, a time shaft, a metallic dial fixed upon the shaft and insulated therefrom, a contact arm arranged 95 to engage one side of the dial, a pair of circular plate members arranged upon the shaft and upon the other side of the dial, a peripheral contact carried by each of the last-named members, means whereby said 100 plate members may be adjusted upon the shaft to bring the peripheral contacts into overlapping relation and provide a continuous contact surface of various lengths, said peripheral contacts being electrically connected to said metallic dial, and a second stationary contact arm arranged to wipe said peripheral contacts with each rotation of the time shaft.

7. In an electric time switch, a time shaft, 110 a dial fixed upon said shaft, a sleeve upon the shaft, a pair of discs fixed upon said sleeve, a ring loose upon the sleeve and disposed between said discs, a peripheral contact carried by the ring and by the disc 115 remote from the dial, a radial arm extending from the disc adjacent the dial and the ring whereby said disc and ring may be adjusted to bring the peripheral contacts into overlapping relation and provide various 120 lengths of continuous contact surface, the distance between the radial arms corresponding to the length of said contact surface in each instance and said arms also indicating the time period on the dial necessary for the contact surface to pass a given point, and a stationary contact arm 125 adapted to wipe upon the peripheral contacts with each rotation of the time shaft.

8. In an electric time switch, a time shaft, 130

a dial fixed upon said shaft, a sleeve upon the shaft, a pair of discs fixed upon said sleeve, a ring loose upon the sleeve and disposed between said discs, a peripheral contact carried by the ring and by the disc remote from the dial, a radial arm extending from the disc adjacent the dial and the ring whereby said discs and ring may be adjusted to bring the peripheral contacts 10 into overlapping relation and provide various lengths of continuous contact surface, the distance between the radial arms corresponding to the length of said contact surface in each instance, a stationary contact arm adapted to wipe upon the peripheral contacts with the rotation of the time shaft, an annular plate of insulating material mounted upon the shaft and its periphery adapted to engage the contact arm 15 and maintain the same out of engagement with said ring and disc until the peripheral contacts engage said arm.

9. In an electric time switch, a time shaft, a dial fixed upon said time shaft, a sleeve upon said shaft, a pair of discs fixed upon said sleeve, a ring arranged between said discs, a peripheral contact carried by one of said discs and said ring, means whereby the discs and ring may be adjusted to arrange the relative position of said overlapping peripheral contacts, a stationary contact arm adapted to wipe upon said peripheral contacts, an annular plate of insulating material arranged upon said shaft, the periphery of which is adapted to engage 35 the contact arm and hold the same out of engagement with said discs and ring during the period said arm is not in engagement with said peripheral contacts, and means whereby the discs and ring, together with 40 the plate of insulating material may be clamped against said dial to rotate with said time shaft as a unit.

DOUGLAS L. PARKHURST.
